ATTORNEY

UNITED STATES PATENT OFFICE

HUGH T. HUGHES, OF CLEVELAND, OHIO

COMBINED CAN OPENER AND SEALING DEVICE

Application filed November 16, 1928. Serial No. 319,893.

The objects of the invention are to provide an improvement in can opening devices by means of which a simple device attachable to any can, can be used to provide a pouring opening in the cover of the can and simultaneously therewith will provide an opening for the admission of air in the cover, thus permitting the liquid therein to flow freely from the pouring opening; also the means 10 employed for piercing the can are subsequently employed to seal the opening they produce, and thus to preserve the contents of the can from fermentation.

The device is particularly applicable for 15 domestic use when applied to cans containing evaporated milk, or syrup or other liquid foods, but can be applied to any can containing liquids that are hermetically sealed and from which it is desired to exclude the 20 air when only a part of the contents has been used.

The invention is illustrated in the accompanying drawings, hereinafter more fully described, and particularly pointed out in the 25 claims.

In the accompanying drawings; Fig. 1 is a plan of a simple form of the device; Fig. 2 is a vertical section thereof; Fig. 3 is a front elevation of the same; Fig. 4 is a plan 30 of an adjustable form of the device; Fig. 5 is a vertical section thereof; Fig. 6 is a front elevation thereof, and Fig. 7 is a plan of a simple form of adjustable device. Fig. 8 shows a modified form of spring therefor; Fig. 9 shows an ornamental holder for table 35 use; Fig. 10 shows one manner of use of an attaching clamp, Figs. 11, 12 and 13 show pivoted levers and circumferential clamps. In these views A is the top of the can; B is 40 a plate having downwardly turned edges C that are forced over the edges of the can to hold the plate in place thereon; D is a metal bar or lever resiliently mounted upon the plate B in such a manner that it can be tilted 45 vertically thereon, and is provided with spaced piercing points or projections E and F respectively, which pass through openings G and H in the plate B and rest upon the cover of the can until the bar D is struck 50 from above by the hand or by a hammer or

any convenient tool, when the points will pierce the cover at G' and H'.

When the bar is lifted the opening G' can be employed for pouring, and air will be admitted through the opening H', and when released the bar will fall, and the points will re-enter the openings they have previously made, and will hermetically seal them, since they will fit the openings closely.

The bar is raised by pressing upon its outer end at I and may be resiliently connected with the plate by means of a spring J integral with the plate, or may be pivoted upon the plate or attaching clamp and pressed upon by the spring K as shown in Figs. 8, 9, 11 and 12.

The pressure of the spring will retain the points pressed into the openings so that air cannot enter the can.

In this manner the contents can be preserved from fermentation until it has all been used.

In Figs. 4, 5, and 6 the modification of a longitudinal adjustment for the plate is shown to adapt it to several sizes of cans and the plate is formed in two portions B, B', one portion sliding in guides B2 in the other portions, and provided with lateral lugs B3 that prevent the parts from separating.

The plate B is branched in front at B4 to 80 provide a space between the arms for pouring so that the liquid will not come in contact with the plate.

In Fig. 7 the plate is provided with a number of spring arms B5 which are resilient 85 enough to permit the plate to be attached to cans of several sizes.

In Fig. 9 an ornamental holder M takes the place of the plate B, and a handle N is attached thereto. In Figs. 10, 11 and 12 a 90 horizontal and circumferential attaching clamp O is shown.

The device is simple, efficient and of slight initial cost and fills a much needed want for a can opening tool that will hermetically seal 95 the can after it has been opened.

In Fig. 12 the attaching clamp is looped at I and the lever D is pivoted in the loop. Other modifications of the device may be made within the scope of the claims.

Having described the invention what I claim as new and desire to secure by Letters Patent is,

1. In a can puncturing and sealing device, 6 a clamping support attachable to said can transversely thereof and a bar or lever resiliently mounted to tilt vertically therein, said bar being provided with spaced vertical pointed projections in line therewith adapted 10 to be forced through the cover of said can, when pressure is applied to said tilting bar a portion of said transverse support being separated therefrom to form a spring, said bar being mounted on said spring.
- 15 2. In a can puncturing and sealing device, a clamping support attachable transversely to the cover of the can, and a bar resiliently mounted to tilt vertically thereon, said bar being provided with spaced pointed projections adapted to be forced through the cover 20 of said can, when pressure is applied to said tilting bar, and plate being made in two portions adjustably connected together.

In testimony whereof I affix my signature.

25 HUGH T. HUGHES.
